ART OF TUNING MAGNETOSTRICTIVE ELEMENTS

Albert Edward Lane, Wenonah, N. J., assignor to
Radio Corporation of America, a corporation of
Delaware

Application November 29, 1944, Serial No. 565,725

3 Claims. (CL. 172—126)

1
This invention relates to the art of tuning magnetostriuctive elements and has special reference to the tuning of tubiform elements constituted of nickel or equivalent (i. e. magnetic) material.

It is sometimes desirable to endow a magnetostriuctive element with a frequency response-characteristic other than that dictated by the physical dimensions of the element per se. To this end it has previously been proposed (see U. S. Patent 942,897) to "load" a magnetostriuctive rod in a manner analogous to that commonly employed in tuning the reeds or tines of a music box, i. e. by soldering a weight to the free end of the rod with a view to altering the effective mass (and hence the frequency) thereof. The trouble with this prior art method of tuning a vibratile element resides not only in the fact that the auxiliary weight or "load" increases the over-all length of the element, but also in the fact that when applied to a bank of magnetostriuctive elements it is usually necessary to employ some auxiliary support or "centering means" for the load on each element. Furthermore, since the weight is soldered to the magnetostriuctive element and is usually of a diameter greater than that of the coil which surrounds the said element it is exceedingly difficult to replace a burnt-out coil.

Accordingly, the principal object of the present invention is to obviate the foregoing and other disadvantages of present day methods of and means for tuning a vibratile element of the general character described.

Another and related object of the present invention is to provide an improved magnetostriuctive unit, of any desired ("fixed") frequency-characteristic, and one characterized by the simplicity and economy of its parts, by its compact structure, and by its trouble-free performance.

The foregoing objects are achieved in accordance with the invention by providing a more or less conventional tubular magnetostriuctive element with a tuning element in the form of a discrete re-entrant portion or "plug" of suitable mass and secured, in a novel manner, within the bore of the tube in a position best calculated to endow the magnetostriuctive element with the desired frequency response-characteristic.

Certain preferred details of construction together with other objects and advantages will be apparent and the invention itself will be best understood by reference to the following specification and to the accompanying drawing wherein:

2
Fig. 1 is a longitudinal section of a magnetostriuctive tube, tuned in accordance with the invention and affixed to a metal diaphragm and

Fig. 2 is an end view of the tuned tube of Fig. 1.
In the drawing the invention is shown as applied to a typical underwater signaling system comprising a metal diaphragm 1 (which may comprise either the skin of the vessel or a wall of a separate water-tight housing) to which a tubular magnetostriuctive element 3 is affixed by soldering or "sweating" one end of the tube within a counter-sunk seat 5, provided for the purpose, in the inner surface of the diaphragm 1. The tubular magnetostriuctive element 3 is surrounded throughout a portion of its length by a signal current carrying coil 7 which is wound on a form 9 and supported on a suitable insulating frame 11 above the surface of the diaphragm 1. Usually the signaling system comprises a plurality or "bank" of magnetostriuctive elements 3 and, in this case, a plate 13 for distributing the flux from one or more polarizing magnets 15 may be mounted in a plane normal to the axis of the said elements. Since the flux distributing plate 13 must be mounted closely adjacent to the free end of the magnetostriuctive element or elements 3 it is apparent that the advantages of such a plate could not be realized in a signaling system wherein the magnetostriuctive element 3 is tuned, as in the prior art, by a mass which extends beyond the end of the said element or elements.

As previously indicated the present invention obviates the foregoing and other objections to prior art tuning devices by the provision of a tuning element or "load" in the form of a re-entrant part or plug 17 of special design, which is mounted within the bore 19 of the magnetostriuctive tube 3 adjacent to the free end thereof.

As clearly shown in Fig. 1 the tuning element 17 for the magnetostriuctive tube 3 comprises three integral sections 17a, 17b, 17c, respectively. The outer section 17a is of a diameter very slightly less than that of the inner diameter of the tube 3 so that it may be entered into the bore 19 of the said tube and affixed to the inner surface thereof as by a compression force applied to the outer surface of the tube, as indicated at 3a. It will be observed that the outer end of the part 17a of the plug 17 is not flush with the outer end of the tube 3 but terminates slightly short of the said end. Thus, should there be any inaccuracy in the length of the said tube, the said end portion of the tube may be ground down, without changing the mass of the plug 17, to provide an

air-gap of the desired length between the tube and the flux distributing plate 13.

Since the outer end portion 17a of the plug is in contact with the inner surface of the tube 3 it serves not only to alter the natural frequency of the said element but also to dampen its vibrations to a limited degree, i. e. to the degree determined by the length of the said end portion. Such a damping action is especially desirable in suppressing odd harmonics which, if propagated, might prove disturbing to installations operating at such higher frequencies. In most cases the described degree of damping is achieved when the length of the part 17a corresponds substantially to the diameter of the bore 19 of the magnetostrictive tube 3. The intermediate portion 17b of the plug, on the other hand, is of a diameter less than that of the bore 19 and, since it does not touch the inner surface of the tube, operates only (by reason of its mass) to alter the frequency of the said tube 3 and not to dampen its oscillations.

The inner end of the tuning element or plug 17 is preferably tapered, as indicated at 17c, to receive a complementarily shaped tool (not shown) for centering the said plug prior to its attachment to the tube 3. The centering and, in most cases, the attachment, of the plug to the tube may take place prior to the attachment of the tube to the diaphragm 1 so that the said tool may be inserted within and withdrawn from the inner end of the tube.

One very real advantage of the present invention is that it permits the manufacturer of magnetostrictive signaling systems to employ magnetostrictive tubes of the same length and accessories (supports-magnets, etc.) of a single size for signaling units designed to operate at different frequencies. Thus, should a manufacturer be called upon to produce a unit to operate at a frequency of say, N kilocycles per second, he could employ an existing magnetostrictive unit having a different, higher frequency response and by the addition of a tuning element of the proper dimensions effect the desired alteration in frequency. Thus, a magnetostrictive element comprising a cold drawn seamless pure nickel tube having an overall length of L , an outside diameter of approximately $L''/6$, wall thickness of approximately $L''/11$ will, when inserted approximately $L''/12$ in a diaphragm, respond to a frequency of $2N$ kc. The same element when provided with a tuning element constituted of mat copper of the following dimensions and similar to the one (17) shown in the drawing will tune the said $2N$ kc. tube to a frequency of N kc.

The dimensions of the tuning element in this case were approximately: outside diameter approximately $L''/6$, overall length approximately $L''/2$, length of head approximately $L''/5.6$, 5 diameter of shank approximately $L''/7.5$, length of shank approximately $L''/3.8$, length of tapered end approximately $L''/15$, angle of taper 30° , weight 12.1 grams.

Various other modifications and applications of 10 the invention will suggest themselves to those skilled in the art. Accordingly, the foregoing should be interpreted as illustrative and not in a limiting sense except as required by the prior art and by the spirit of the appended claims.

15 I claim:

1. The combination with a tubular magnetostrictive element having a fixed-end and a free-end and dimensioned to respond to a certain fundamental frequency, of a nonmagnetic member secured to the interior of said tubular element adjacent to the said free-end thereof, said nonmagnetic member comprising a body portion of a length corresponding substantially to the inner diameter of said tubular element and a 20 concentric dependent portion of a diameter less than that of said body portion.

2. The invention as set forth in claim 1 and wherein said free-end of said tubular magnetostrictive element extends slightly beyond the adjacent end of said body portion of said nonmagnetic member.

3. In combination, a magnetostrictive tube having a bore of substantially uniform diameter, and a tuning element for said tube comprising a 35 head portion constituted of non-magnetic material seated within the bore of said tube and a dependent frequency determining portion of a diameter substantially less than that of said bore extending into said tube.
